UNITED STATES PATENT OFFICE.

ANDREW J. MANGINI, OF WARREN, PENNSYLVANIA.

HAND-TOOL.

1,331,348.

Specification of Letters Patent.

Patented Feb. 17, 1920.

Application filed August 8, 1918. Serial No. 248,881.

To all whom it may concern:

Be it known that I, ANDREW J. MANGINI, a citizen of the United States, residing at Warren, in the county of Warren and State 5 of Pennsylvania, have invented new and useful Improvements in Hand-Tools, of which the following is a specification.

The present invention relates to improvements in hand tools or implements, and more especially to those of the general class embodying a handle and blades or similar operative parts adapted to be removably and interchangeably fitted to the handle. The primary object of the invention is to provide a novel and improved tool of this class whereby the different interchangeable blades or operative parts may be easily and quickly removed from the handle and yet a firm connection is provided between the handle and the blade or operative part, the tool having preferably a holder adapted to receive the blade or equivalent part, this holder being pivotally or movably connected to the handle whereby relative movement between the holder and the handle will automatically and forcibly eject the blade or operative part therefrom to enable another blade or other operative part to be readily substituted.

30 To these and other ends, the invention consists in certain improvements, and combinations and arrangements of parts, all as will be hereinafter more fully described, the novel features being pointed out particularly in the claims at the end of the specification.

In the accompanying drawing:

Figure 1 is an elevation, partly in section, of a hand tool constructed in accordance 40 with the present invention.

Fig. 2 is a view similar to Fig. 1 but showing a part thereof in section in a plane at a right angle to the plane of the section in Fig. 1.

Fig. 3 represents a longitudinal section of the hand tool showing the blade holder swung into a position to eject the blade, and

Fig. 4 represents, on an enlarged scale, a section on the line 4—4 of Fig. 1.

50 Similar parts are designated by the same reference characters in the several views.

The present invention is applicable, generally, to tools or implements of various kinds, although it is particularly applicable

55 to hand tools or implements of the class adapted to removably and interchangeably

receive different blades or operative parts. The preferred embodiment of the invention is shown in the accompanying drawing and will be hereinafter described in detail. It 60 is to be understood, however, that the invention is not restricted to the precise construction shown as equivalent constructions are contemplated and will be included within the scope of the claims.

65 The tool, as shown, comprises a handle 1 which may be composed of wood or other appropriate material, a ferrule or fitting 2 of metal or other suitable rigid material being fixed to the handle. This ferrule or fitting has a flat tongue 3 projecting from its end and the extremity of this tongue is formed with an intermediate notch or slot 4 and diverging cam surfaces 5 leading in opposite directions from the notch. A holder 75 6 is provided to receive the different blades or other operative parts, a screw-driver blade 7 being shown in the present instance. The holder is preferably formed with a cylindrical socket 8 to receive a correspondingly shaped shank 9 on the blade and the holder is also formed with a slot or kerf 10 to fit the tongue 3 attached to the handle. The blade is preferably formed on its end with a rectangular key or tang 11 which fits 85 into the slot or kerf 10 of the holder when the blade is inserted into the holder, the engagement of the opposite flat sides of the key with the opposed parallel walls of the slot 10 of the holder forming a driving connection between the holder and the blade. The base of the holder 6 is adapted to abut against the end of the ferrule or fitting 2 and when the holder is in this position the key 11 on the blade will be seated in the 95 notch 4 in the tongue 3. The holder is operatively connected to the ferrule 2 by a pivot pin 12 which is secured in the holder and extends through a slide 13 which is guided to reciprocate in a slot 14 formed 100 longitudinally in the tongue 3, this pin and slide permitting relative longitudinal and pivotal movement between the blade holder and the handle. Preferably, a stem or rod 15 is attached to the slide 13 and extends 105 through the forward wall of the ferrule 2 and a compression spring 16 is interposed between the ferrule and a nut or abutment 17 on the stem or rod. The spring thus acts to draw the blade holder toward the handle 110 with the rear end of the holder in abutment with the forward wall of the ferrule and the

spring also serves to normally retain the blade holder in longitudinal alinement with the handle.

In using a tool constructed as shown and described, the blade or other operative part which it is desired to use is inserted into the socket 8 of the holder so that the key 11 on the inner end of the blade is seated in the notch 4 of the tongue 3 and between the walls of the slot 10 in the holder. The blade is then operatively connected to the handle and the tool may be used for its intended purposes, the blade holder and handle being in alinement during use of the tool and such alinement is maintained by the abutment of the rear end of the holder against the forward end of the ferrule, the spring serving to normally maintain the abutting engagement of these parts. When it is desired to remove a blade for any purpose, such for example as for substitution of another blade, it is only necessary to retract the holder longitudinally of the handle and then swing the holder laterally in either direction, as shown for example in Fig. 3. By so swinging the holder and the blade therein, the key 11 on the blade is caused to engage one of the cam surfaces 5 on the forward end of the tongue 3, and as the swinging of the holder and blade continues this cam surface will forcibly eject the blade from the holder, the longitudinal movement of the holder relatively to the handle being limited by the abutment of the slide 13 against the forward end of the slot 14. After the blade has been ejected the spring 16 will automatically restore the holder to its normal position in alinement with the handle and with its rear end abutting against the ferrule. The holder is then ready to receive another blade or operative part.

A hand tool embodying the present invention enables screw-driver blades, scrapers, chisels and other operative parts to be readily and easily interchanged with respect to a handle common to all the blades or operative parts, thus avoiding delays heretofore experienced in the use of tools of this general class, due to the sticking of the blade in the handle or holder, the blade or operative part, according to the present invention, being instantly removable from the handle without the aid of any attachment or another tool. Furthermore, the blade or operative part is securely keyed or connected to the holder and the holder in turn is securely coupled or connected to the handle, and hence the maximum power which can be applied to the handle will be transmitted without strain or breakage to the blade or operative part.

I claim as my invention:

1. A tool comprising a support, a holder having a socket to detachably receive a

blade, said holder being connected to the support and tiltable with respect thereto, and means operated by relative tilting movement between the holder and support for forcibly ejecting the blade from the holder. 70

2. A hand tool comprising a handle, a holder pivotally related to the handle and adapted to interchangeably receive different blades or operative parts, and cam means operated by relative pivotal movement between the holder and handle for ejecting a blade or operative part from the holder. 75

3. A tool comprising a handle, a holder movable laterally with respect to the handle and adapted to removably receive a blade or operating part, and means including a cam attached to the handle and operative upon the blade during relative lateral movement between the holder and handle for ejecting the blade from the holder. 80

4. A tool comprising a handle having a tongue fixed thereto and provided with a cam surface, and a blade holder slotted to fit said tongue and capable of displacement laterally thereof, the cam on said tongue being operative on a blade in said holder during such lateral displacement to eject the blade from the holder. 90

5. A tool comprising a handle having a tongue rigidly fixed thereto and provided with a cam surface on its extremity, a blade holder slotted diametrically to straddle said tongue, and means pivotally connecting said holder to the handle and permitting relative tilting movement between such parts, 100 said cam on the tongue being operative on a blade in the holder during such tilting movement to eject the blade from the holder.

6. A tool comprising a handle having a tongue rigidly fixed thereto and provided with a cam surface thereon, the handle also having abutments at opposite sides of the tongue, a blade holder tiltably fitted to said tongue and having abutments adapted to co-operate with the abutments on the handle, 110 and means pivotally connecting the holder to the handle, the cam surface on the tongue being operative on a blade in the holder during relative pivotal movement between the holder and handle to eject such blade. 115

7. A tool comprising a handle provided with a ferrule having a flat tongue projecting therefrom with an intermediate notch and diverging cam surfaces at the extremity, and a blade holder tiltably laterally on 120 said tongue, a part of a blade in the holder being adapted to be seated in said notch in the tongue while the holder and handle are in alinement, and one of said cam surfaces being operative on such part of the blade 125 when the holder is tilted relatively to the handle, thereby ejecting the blade from the handle.

8. A tool comprising a handle provided with a tongue projecting therefrom and 130

abutments at opposite sides thereof, a blade holder slotted diametrically to straddle said tongue and having abutments adapted to co-operate with those on the handle, and means 5 pivotally connecting the holder to the handle and acting normally to maintain the abutments of the holder in engagement with those on the handle and permitting relative tilting movement between the holder and 10 handle, the tongue being operative on a

blade in the holder, during such relative tilting movement, to eject the blade.

In testimony whereof I have hereunto set my hand in presence of the subscribing witnesses.
